UNITED STATES PATENT OFFICE

145,611

DESIGN FOR A BOTTLE HOLDER

Easter M. Butterfield, Redondo Beach, Calif.

Application November 13, 1945, Serial No. 123,676

Term of patent 14 years

(Cl. D83—8)

To all whom it may concern:

Be it known that I, Easter M. Butterfield, a citizen of the United States, residing at Redondo Beach, in the county of Los Angeles, State of California, have invented a new, original, and ornamental Design for Bottle Holder, of which the following is a specification, reference being had to the accompanying drawing, forming part thereof.

The dominant features of the design reside in the portions shown in full lines.

I claim:

The ornamental design for a bottle holder, as shown and described.

EASTER M. BUTTERFIELD.
